FOLDING TABLE AND BENCH CONSTRUCTIONS
Claude G. Kanzelberger, Two Rivers, Wis., assignor to
Hamilton Manufacturing Company, Two Rivers, Wis.,
a corporation of Wisconsin

Filed Sept. 18, 1961, Ser. No. 138,750
12 Claims. (Cl. 108—37)

This invention relates generally to folding table and bench constructions, and more particularly to a transversely folding table and bench construction which is stored in a wall pocket or cabinet.

The primary object of the present invention is to provide a novel table assembly which includes a table, benches and wall pocket and which will permit compact storage of the table and benches in the wall pocket or cabinet.

It is a further object to provide an assembly of the foregoing character in which the table and benches may be easily and conveniently moved to a horizontal open position or to the closed position for storage within the pocket.

Still another object is to provide in such assembly novel locking or retaining means for positively retaining or locking the table and benches within the wall pocket or cabinet.

A more specific object is to provide a novel table and bench assembly including a wall pocket, in which the table and benches are foldable transversely thereof and movable into a vertical position within the wall pocket or cabinet, with means for securing the table and benches, both at the bottom and top thereof, within the wall pocket.

Further objects and advantages of the invention will become apparent from the following description taken in conjunction with the drawings in which:

FIG. 1 is a side elevational view of the table structure of an assembly embodying the features of the invention and showing the table structure in open position;

FIG. 2 is an end elevational view of the right-hand end of the table structure shown in FIG. 1;

FIG. 3 is an enlarged view of a portion of the assembly shown in FIG. 2;

FIG. 4 is a side elevational view of the portion shown in FIG. 3;

FIG. 5 is a view of the underside of the table structure of FIG. 1 and taken substantially along the line 5—5 of FIG. 1 and with the portion shown in FIGS. 3 and 4 removed;

FIG. 6 is substantially a top plan view of the wall pocket or cabinet structure with the top wall thereof removed;

FIG. 7 is a cross sectional view taken substantially along the line 7—7 of FIG. 6;

FIG. 8 is a cross sectional view taken substantially along the line 8—8 of FIG. 6;

FIG. 9 is an enlarged view similar to FIG. 8 but showing portions of the table structure therein;

FIG. 10 is a side elevational view of a bench structure of the assembly and showing the bench structure in its open position;

FIG. 11 is a view of the underside of the bench structure of FIG. 10 and taken substantially along the line 11—11 of FIG. 10;

FIG. 12 is an enlarged view of a portion of the structure shown in FIG. 10;

FIG. 13 is a side elevational view of the portion shown in FIG. 12;

FIG. 14 is an enlarged elevational view of locking means for the table structure;

FIG. 15 is a side elevational view of the locking means shown in FIG. 14;

2

FIG. 16 is an enlarged elevational view of locking means for the bench structure; and

FIG. 17 is a top plan view of the locking means shown in FIG. 16.

Generally, an assembly embodying the present invention comprises four basic parts, a table structure, two identical bench structures, and a wall pocket or cabinet for storing the table and bench structures. The table structure comprises two top members which are positioned in an end-to-end horizontal alignment when the assembly is open, and the adjacent ends of the two top members are hinged to each other and are movable upwardly to place them in substantially vertical and parallel relation when the table is in a closed position within the wall pocket or cabinet. When open, the table structure is supported at its ends by two end leg structures and at its center, where the top members are pivotally connected, by a center leg structure.

One end of the table structure is provided with means for pivotally securing said end in the wall pocket or cabinet. The leg structures are pivotally connected to the top members and are adapted to fold against and between the top members when the assembly is closed. The end leg structure at the end opposite that provided with the pivotal securing means is arranged to support the table structure when in the closed position in the wall pocket, and said opposite end of the table structure is provided with means for locking it to the first mentioned end when closed. To firmly hold the table structure in the wall pocket, the hinge connecting the top members is locked in the wall pocket in the upper part thereof. Thus, the top members are held in the wall pocket both at their upper and lower ends when the assembly is closed.

The two bench structures are positioned on the respective sides of the table structure when open and are stored one on each side of the table structure in the wall pocket. The bench structures are substantially identical to each other and are similar in construction to the table structure.

In detail, the table structure comprises two top members 10 and 11 (see FIGURES 1 and 5). The top members 10 and 11 are substantially rectangular and equal in size. Each of the top members 10 and 11 has secured to the underside thereof in laterally spaced relation a pair of aprons 12 and 13. Each of the aprons 12 and 13 is in the form of an inverted channel with the edges of the flanges turned inwardly. The top members 10 and 11 are pivotally interconnected in an end-to-end relationship by a center leg structure indicated generally at 16. The center leg structure 16 comprises a pair of vertical legs 21 secured together as a unit by a crosspiece 17 (see FIGURE 1). Each leg 21 is pivotally connected by a pin 24 to a pair of channel shaped brackets 19 and 20. The brackets 19 and 20 are secured to the underside of the top members 10 and 11 inwardly of the aprons 12 and 13 as shown in FIGURE 5. One end portion of the flanges of each of channel bracket 20 is offset inwardly and inserted between the flanges of the adjacent end of one channel bracket 19, and the pivot pin 24 extends through the interleaved flanges of the channel brackets 19 and 20 to pivotally interconnect the channel brackets as well as the leg 21. To equalize the folding movement of the top members 10 and 11 relative to the center leg structure 16, a pair of links 22 are pivotally connected, as at 26, to opposite sides of a collar 25 slidable on the leg 21. The other end of each link 22 is pivotally connected to a bracket 27 by a pin 28, and each of the brackets 27 is secured, as by welding, to one of the channel brackets 19 and 20 as shown in FIGURE 5. The lower end of each leg 21 is provided with a floor cap 30.

The table structure also includes a pair of end leg structures indicated generally at 32 and 40. The end leg structure 32 comprises a pair of vertical legs 35 connected

by a crosspiece 33. The legs 35 are provided with casters 36 at their lower ends. The upper ends of the legs 35 are secured to the underside of the top member 10 by channel brackets 34 positioned inwardly of the aprons 12 and 13, as shown in FIGURE 5. The upper end of each leg 35 is pivotally connected within the channel bracket 34 by a pin 38. The distance from the axis of pins 38 to the bottom of the casters 36 is greater than the distance from the axis of pins 38 to the outer end of the table top section 10. With this arrangement, the casters 36 engage the floor throughout the folding movement of the assembly.

The end leg structure 40 for the top member 11 comprises a pair of vertical legs 43 secured together as a unit by a crosspiece 41 and having casters 44 at their lower ends. Each leg 43 at its upper end is pivotally connected by a pin 46 to a channel bracket 42, and the latter is secured to the underside of the top member 11 and are positioned inwardly of the aprons 12 and 13 and inwardly of the channel brackets 34 of the end leg structure 32, as shown in FIGURE 5, so that the end leg structures 32 and 40 do not interfere with each other in the folded condition. The distance between the axis of the pins 46 and the bottom of the casters 44 is less than the distance from the axis of pins 46 to the adjacent end of the top member 11 so that in the closed position of the assembly, the casters 44 are disposed above the lower edge of the top member 11, as shown in FIGURE 9.

To control the movement of the end leg structures 32 and 40 during folding and unfolding, the assembly further includes a pair of stretcher bars 50. One end of each stretcher bar 50 is pivotally connected to a bracket 51 by a pin 52, and one of the brackets 51 is secured to the upper side of the crosspiece 33 of the leg structure 32 and the other bracket 51 is secured to the upper side of the crosspiece 41 of the leg structure 40. The other end of each stretcher bar 50 is pivotally connected to a bracket 55 by a pin 56, and the brackets 55 are secured to the underside of the top members 10 and 11 adjacent the center thereof and adjacent the pivotally connected ends thereof. The stretcher bar 50 which is connected through brackets 51 to the end leg structure 32 is connected at the other end thereof through brackets 55 to top member 11, and the other stretcher bar 50 is pivotally connected to top member 10 and to the end leg structure 40. The stretcher bars 50 maintain the end leg structures 32 and 40 substantially upright in the open position of the table, and cause the end leg structures 32 and 40 to be folded substantially parallel to the top members 11 and 11 in the closed position of the assembly.

The table structure also includes cushioning means for cushioning movement of the table structure to its open position and for assisting in moving the table structure to its closed position. In the present instance, the cushioning means is shown as comprising a hydraulic cylinder assembly 60 comprising a cylinder having a piston rod extending from one end thereof. The hydraulic cylinder assembly 60 further includes a spring and certain internal porting (not shown) for yieldingly resisting the movement of the piston rod into the cylinder portion thereof and thereby cushion the opening movement of the table structure. On movement toward closed position, the piston rod is spring-biased outwardly of the cylinder portion thereof to assist in the closing movement. The lower end of the cylinder portion is provided with a bearing block 61 secured thereto, and the upper end of the piston rod is also provided with a bearing block 62 secured thereto. The bearing blocks 61 and 62 are connected to the top members 10 and 11 in a manner to produce relative movement of the cylinder portion and piston on folding and unfolding movement of the top members. To this end, two channel brackets 65 and 66 are provided. As shown in FIGURE 5, channel brackets 65 and 66 are secured to the underside of top members 10 and 11 substantially at the center thereof. The flanges of channel bracket 65 at one end thereof are offset inwardly to permit

the offset portion to be positioned between the flanges at one end of the channel bracket 66 and the interleaved ends of the channel brackets 65 and 66 are pivotally connected by a pin 68. The pin 68 also extends through the bearing block 62 with the bearing block 62 located between the flanges of the channel brackets as shown in FIGURE 3. A pair of rollers 70 are also journaled one on each end of the pin 68. Snap rings 71, one at each end of the pin 68 maintain the described assembly together as a unit.

To actuate the cylinder portion of the hydraulic cylinder assembly 60, a pair of links 73 and a pair of links 74 are also provided. One link 73 and one link 74 are pivotally interconnected at one end of the bearing block 61 by a pin 75, while the other link 73 and the other link 74 are pivotally interconnected at the other end of the bearing block 61 by the pin 75. The other ends of the links 73 are pivotally carried on the ends of a pin 77 which is mounted in the flanges of the channel bracket 65 intermediate the ends thereof, and the other ends of the links 74 are pivotally connected to the channel bracket 66 intermediate the ends thereof by a pin 79 which extends through the flanges of the channel bracket 66. The links 73 and 74 maintain the hydraulic cylinder assembly 60 in a vertical alignment with the axis of pin 75 substantially vertically below the axis of pin 68.

As heretofore mentioned, the assembly includes a wall pocket or cabinet to receive the table structure when folded. The wall pocket or cabinet is shown in FIGURES 6, 7, 8 and 9 and in the present instance comprises a table pocket, indicated generally at 100, and two bench pockets indicated generally at 101 and 102. The table pocket 100 comprises a pair of spaced apart side walls 103 and 104, a back wall 105, a bottom wall 106 and a top wall 107. The distance between the side walls 103 is slightly greater than the width of the top members 10 and 11 and the height of the opening in the wall pocket 100 is somewhat greater than the length of each top member 10 and 11.

One end of the top member 11 is arranged to be pivotally connected to the wall pocket and to this end vertically extending slots 82 are formed in the side walls 103 and 104 as shown in FIGURE 8. The slots 83 at the outer side of the side walls 103 and 104 are closed by channel members 109. Pivotal connecting means 82 is provided on one end of the top member 11 for securing said end to the wall pocket 100, the connecting means 82 cooperating with the slots 83 of the wall pocket. The connecting means 82, in the present instance, comprises a pair of rods 84 slidably mounted in the aprons 12 and 13 and adapted to be forced outwardly into the slots 83 in the wall pocket. For forcing the rods 84 outwardly, a cam member 85 is provided. The cam member 85 which is generally elliptical in shape and has a handle portion 85a extending from one side thereof is rotatably supported by a pin 89 mounted in a bracket 90. The bracket 90 is U-shaped, having a central plate portion which is secured to the underside of the table top section 11 adjacent the extending marginal edge thereof, and an upstanding flange portion 90a at each end thereof. The flange portions 90a are provided with openings therethrough to receive the inner ends of the rods 84. The cam member 85 is thus positioned between the ends of the rods 84 and on rotation of the cam member 85, the rods will be forced outwardly for engagement in the slots 83 in the wall pocket 100. The rods 84 are spring urged inwardly to hold them against the cam member 85. Thus, each of the rods 84 is provided with a cross pin 92 and a coil spring 86 is positioned on the rod between the pin 92 and a flange of the aprons 12 or 13. The upper ends of the slots 83, as shown in FIGURE 8, are positioned at a point at least as high as the spacing of the rods 84 from the floor in open position of the table. It is thus apparent that the cam member 85 may be manually rotated to move the outer ends of the rods 84 outwardly into the slots 83 to pivot-

ally connect the end of the top member 11 to the wall pocket.

When the end of the top member 11 is pivotally connected to the wall pocket 100, the pivotally connected ends of the top members 10 and 11 are raised and moved toward the wall pocket. During such movement, the rods 84 move downwardly in the slots 83 until they rest on the lower ends of the slots, and the top member 11 swings toward a parallel relationship with the end leg structure 40. When the rods 84 reach the bottom of the slots 83, further inward movement of the top member 11 lifts the end leg structure 40 so that its casters longer contact the floor.

During the folding movement, the casters 36 of the end leg structure 32 remain in contact with the floor, since the length of the end leg structure 32 is greater than the distance from its pivotal connection with the top member 10 to the end of the top member. However, the length of the end leg structure 32 is such that, during the final part of the movement of the table structure into the wall pocket, the top member 10 is lifted. Since the top members 10 and 11 are pivotally connected, the top member 11 is likewise raised, moving the rods 84 upwardly a short distance in the slots 83.

Such lifting movement of the top members 10 and 11 is utilized to effect a locking engagement of the top members with the wall pocket 100 at the upper end thereof. However, it is desirable that the locking means provided for this purpose avoid contacting the top members 10 and 11 to prevent marring of the top members. To this end, the locking means provided cooperates with the hinge connection between the top members 10 and 11. Thus, locking means in the form of a locking plate 110 is mounted on the underside of the top wall 107 of the wall pocket. The locking plate 110 is preferably mounted at the center of the wall pocket to cooperate with the rollers 70 provided at the hinge connection of the cushioning means 60 with the top members 10 and 11.

As shown in FIG. 9, the locking plate 110 is secured to the top wall 107 of the wall pocket and projects downwardly therefrom. On its lower face, the locking plate 110 is provided with an arcuate opening 110b of a diameter to receive the rollers 70 and two guide surfaces 110a diverging downwardly therefrom. As the top members 10 and 11 are lifted by the action of the end leg structure 32 during the final part of the closing movement, the rollers 70 engage one of the guide surfaces 110a and are guided into the arcuate opening 110b. Thus, the locking plate 110 retains the rollers 70 in the arcuate opening and secures the upper end of the table structure to the wall pocket.

Latching means is also provided for locking the top member 10 to the top member 11 in the closed position of the assembly. Such latching means comprises a latch assembly, indicated generally at 130, and a strike indicated at 131 in FIGURES 5, 14 and 15. The latch assembly 130 comprises a base 132, a handle 133, a latch member 134, and a spring 135. The base 132 is secured to the underside of the top member 10 adjacent the end thereof opposite to the end connected to top member 10 and substantially at the transverse center of top member 10 as shown in FIGURE 5. The base 132 is provided with an upstanding bearing portion which pivotally carries one end of the somewhat U-shaped handle 133. The latch member 134 is rigidly secured to the portion of the handle 133 which is journaled in the base member 132. The latch member 134 includes a hook portion 134a and a stop portion 134b. The spring 135 is coiled about a portion of the handle 133 and at one end thereof engages the base 132 and at the other end thereof engages the latch member 134 to bias the latch member 134 with the stop portion 134b against the base 132 and with the hook portion 134a positioned outwardly of the base 132. The latch member 134 thus normally extends away from the underside of the top member 10. In this position of the

latch member 134, the handle 133 is inclined away from the underside of the top member 10 and toward the end thereof.

The strike 131 is secured to the underside of the top member 11 adjacent the end opposite the end pivotally connected to the top member 10, so that, when the table is in the closed position, the strike 131 is engaged in the latch member 134. The strike 131 is generally U-shaped and has an extending end 131a spaced from the underside of the top member 11 and engageable by the latch member 134. The latch member 134 is further provided with a camming surface 134c which engages the extending portion 131a of the strike 131, upon closing of the table, to automatically permit the hook portion 134a of the latch member to engage the extending portion 131a of the strike to lock the two top members 10 and 11 together. When locked, the latch member 134 may be readily released by reaching under the lower edge of the top member 10 and drawing the handle 133 toward the top member 10.

The engagement of the latch member 134 with the strike 131 securely holds the table structure within the wall pocket 100. Thus, the rollers 70 of the hinged connection of the top members 10 and 11 can only be released from the locking plate 110 by downward movement of the top members 10 and 11, and such downward movement can occur only when the lower end of the top member 10 moves outwardly from the wall pocket.

As heretofore mentioned, the assembly includes two bench structures located at the respective sides of the table structure and adapted to be folded into the bench pockets 101 and 102 of the wall pocket or cabinet. Since the two bench structures are substantially identical, only one need be described. The bench structure, which is shown in detail in FIGURES 10 through 13, is generally similar to the table structure but differs primarily from the table construction in that the bench structure is of course lower and is not provided with a hydraulic cylinder assembly at the center thereof. The bench structure comprises two seat sections or top members 150 and 151. The top members 150 and 151 are substantially rectangular and equal in size and further are of a length substantially equal to the length of the table top members 10 and 11. Each of the top members 150 and 151 is provided with aprons 152 and 153. Each of the aprons 152 and 153 is an inverted channel in cross-section with edges of the flanges of the channel bent inwardly. The aprons 152 and 153 are secured to the underside of and at the side edges of the top members 150 and 151.

The seat sections 150 and 151 are pivotally interconnected, in an end-to-end relationship when open, by a pair of center leg structures indicated generally at 155. Each center leg structure comprises a channel bracket 156, a channel bracket 157, a leg 158, and a pair of links 159. Each channel bracket 156 is secured to the underside of the top member 150 and within the aprons 152 or 153 as shown in FIGURE 11. The channel brackets 157 are correspondingly secured to the underside of the top member 151. One end portion of each channel bracket 157 is disposed between the flanges of one channel bracket 156, and the upper end of the leg 158 is positioned between the interleaved ends of the channel brackets 156 and 157. A pivot pin 162 extending through the interleaved ends of the channel brackets 156 and 157 and the upper end of the leg 158 pivotally interconnects those three members. Each of the center leg structures 155 further includes a roller 163. The two rollers 163 are journaled on the inner ends of the pivot pins 162 and are retained thereon by snap rings 164.

The links 159 equalize the movement of the top members 150 and 151 relative to the center leg structures 155. One end of the links 159 are pivotally connected, as at 166, to the opposite sides of a collar 167 slidable on the upper portion of each leg 158. The other ends of the links 159 are pivotally connected to brackets 170 by a pin 171 which extends through the side walls of the

channel brackets 156 and 157, the brackets 170 being secured in the channel brackets 156 and 157. The axis of pins 162 is positioned below the axes of pins 171 in the open position of the bench, so that in the closed position of the bench, similar to the closed position of the table shown in FIG. 9, there is space between the top members 150 and 151 for the leg structures. The lower end of each leg 158 may be provided with a floor cap 173.

An end leg structure for top member 150, indicated generally at 175, is provided. The end leg structure 175 comprises a pair of legs 178 interconnected as a unit by a crosspiece 176, the legs having casters 180. The end leg structure 175 also includes a pair of channel brackets 177. Each channel bracket 177 is secured to the underside of the seat section 150 and against the aprons 152 and 153. The upper end of each leg 178 is pivotally connected within a channel bracket 177 by a pin 181. The distance from the axis of pins 181 to the bottom of the casters 180 is greater than the distance from the axis of pins 181 to the outer or extending end of the top member 150. This arrangement provides that, in the closed position of the bench, the casters 180 will engage the floor with the end of the top member 150 positioned slightly above the floor.

An end leg structure indicated generally at 185 for the seat section 151 is provided. The end leg structure 185 comprises a pair of legs 188 having casters 190 at their lower ends and secured together as a unit by a crosspiece 186. The end leg structure 185 includes a pair of channel brackets 187 secured to the underside of the seat section 151 against the aprons 152 and 153 as shown in FIG. 11. The upper end of each leg 188 is pivotally connected within the channel brackets 187 by pins 191. The distance between the axis of the pins 191 and the bottom of the casters 190 is less than the distance from the axis of the pins 191 to the outer or extending end of the top member 151, so that, in the closed position of the bench, the casters 190 are disposed above the lower edge of the top member 151.

The bench structure further includes a pair of stretcher bars 193. One of the stretcher bars 193 is pivotally connected as at 194 to the upper side of the crosspiece 176 of the end leg structure 175, while one end of the other stretcher bar 193 is pivotally connected as at 195 to the upper side of the crosspiece 186 of the end leg structure 185. The other end of each stretcher bar 193 is pivotally connected to a bracket 196 by a pin 197, and each of the brackets 196 is secured to the underside of one of the top members 150 and 151 between the aprons 152 and 153. The stretcher bar 193 which is connected to end leg structure 175 is connected at the other end thereof by bracket 196 to the top member 151, and the other stretcher bar 193 is connected between the top member 150 and the end leg structure 185. The stretcher bars 193 maintain the end leg structures 175 and 185 substantially upright in the open position of the bench and cause them to be folded substantially parallel to the top members 150 and 151 in the closed position of the bench structure.

As heretofore described, the wall pocket includes bench pockets 101 and 102 at the respective sides of the table pocket 100. The bench pockets 101 and 102 are substantially similar in construction to the table wall pocket 100. Bench wall pocket 101 comprises a pair of spaced apart side walls 112 and 113, a back wall 114, a bottom wall 115 and a top wall 116. The side walls 112 and 113 are provided with vertical slots 117 and the underside of the top wall 116 is provided with a locking plate 118. Wall pocket 102 comprises a pair of spaced apart side walls 120 and 121, a back wall 122, a bottom wall 123 and a top wall 124. The side walls 120 and 121 are provided with slots 117 and the underside of the top wall 124 is provided with a locking plate 118. The locking plates 118 are substantially similar in configuration to the locking plate 110 of the table wall pocket 100.

The bench further includes pivotal connecting means,

indicated generally at 200, which is substantially similar to the pivotal connecting means 82 of the table. The pivotal connecting means 200 is provided for locking one end of the bench structure in the slot 117 of the wall pocket 101 or 102. The pivotal connecting means 200 comprises a pair of rods 201, a cam member 202, and a pair of coiled springs 203. The cam member 202 is rotatably connected to a U-shaped plate 204 which is secured to the underside of the top member 151 adjacent the extending end thereof remote from the hinged end. The upstanding flange portions at each side of the bracket 204 are provided with holes in which one end of the rods 203 are slidably supported. The other end of the rods are slidably supported in holes in the flanges of the aprons 152 and 153. The coiled springs 203 are carried about the rods 201 and one end of each of the coiled springs 203 engages a pin carried by one of the rods 201 and the other end of each coiled spring 203 engages one of the aprons 152 and 153 to bias the rods 201 toward the cam member 202. When the long dimension of the cam member 202 is positioned between the cooperating ends of the rods 201, the other ends of the rods 201 extend outwardly of the side edges of the section 151 and when the cam member 202 is rotated about its axis to place the short dimension thereof between the ends of the rods 201, the rods 201 are retracted by the springs 203. The upper ends of the slots 117 as shown in FIG. 7 are positioned at a point at least as high as the spacing of the axis of the rods 201 from the floor in the open position of the bench. Thus, the end of the bench structure may be moved into the bench pocket 101 or 102 and the rods 201 extending into the slots 117 to pivotally connect the top member 151 to the wall pocket.

The benches are folded into the wall pockets 101 and 102 in a manner similar to that for the table. In other words, the center of the bench is raised and the extending end of the bench top member 150 is pushed toward the wall pocket. The bench will roll on the casters 180 and 190 as the bench is being folded, and the extending ends of the bench top members 150 and 151 will approach the floor, the rods 201 moving downwardly in the slots 117. When the rods 201 reach the lower end of the slots 117, further folding movement of the bench will cause the casters 190 to be raised upwardly from the floor. The lower end of each slot 117 is at a height above the bottom walls 115 and 123 which will permit the rollers 163 of the center leg assemblies 155 to move below the lowest depending portion of the locking plate 118. As the casters 180 of the end leg structure 175 are moved into the wall pockets 101 and 102, the entire folded bench structure will be raised by the end leg structure 175 to cause the rollers 163 to engage one of the guide surfaces of the locking plate 118 and be guided into the arcuate opening thereof.

A further locking means is provided for locking the top member 150 to the top member 151 in the closed position of the table. This locking means, which functions similarly to the latch member 130 and strike 131 of the table, comprises latch structure indicated generally at 207 and a strike indicated generally at 208 in FIGS. 11, 16 and 17. The latch structure 207 comprises a base 210, a latch member 211 and a spring 212. The base 210 is secured to the underside of the top member 150 and against the apron 152 adjacent the extending end thereof. The base 210 is provided with an upstanding bearing portion which pivotally carries a shaft secured to the latch member 211. The latch member 211 comprises a handle portion 211a which may be engaged by a person's hand, a hook portion 211b, a stop portion 211c and a camming surface 211d. The spring 212 is coiled about a portion of the shaft of the latch member 211 and at one end thereof engages the base 210 and at the other end thereof engages the latch member 211 to bias the latch member 211 with

the hook portion 211b positioned outwardly of the base member 210. In this position of the latch member 211, the handle portion 211a is manually movable toward the top member 150 to pivot the hook portion 211b toward the extending end of the seat section 150.

The strike 208, which preferably is somewhat U-shaped, is secured to the underside of the top member 151 and against the apron 153 thereof at a position spaced from the extending end of the seat section 151 so that, when the bench is in the closed position, the latch member 211 engages the strike 208 as shown in FIG. 16. The cam surface 211b of the latch member 211 engages the strike 208, when the bench is moved to the closed position, to automatically swing the latch member 211 past the strike 208 and permit the spring 212 to swing the latch member into locking position with the strike 208.

As with the table structure, the bench structure is held firmly in the wall pocket when the latch member 211 is in locking engagement with the strike 208. Thus, such locking engagement prevents outward movement of the lower end of the top member 150 and consequently the end leg structure 175 maintains the bench structure in its raised position with the rollers 163 engaged in the arcuate opening of the locking plate 118 at the top of the wall pocket. At the lower end of the bench structure, the top member 151 is held in the wall pocket by the rods 201 and the top member 150 is secured to the top member 151 by the latch member 211. Thus, the entire bench structure is securely retained in the wall pocket. The bench structure may be released by reaching under the lower edge of the top member 150 and manually moving the handle portion 211a toward the top member 150 to release the latch member 211 from the strike 208.

I claim:

1. A foldable table-top assembly comprising two top members, hinge means pivotally interconnecting one end of each of said top members for holding said members in horizontal end-to-end relation when the assembly is open and in vertical parallel relation when the assembly is closed, a wall pocket to receive said top members when the assembly is closed, means carried at the other end of one of said top members for pivotally connecting said other end in said wall pocket, means for raising said top members a certain distance upwardly attendant to the folding thereof into said wall pocket, and locking means mounted in said wall pocket in the upper part thereof and positioned to receive said hinge means when said top members are raised said distance and thereby retain said top members in the closed position in said wall pocket.

2. An assembly according to claim 1, in which said hinge means extends beyond the adjacent ends of said top members when the assembly is in closed position to project into said locking means.

3. An assembly according to claim 1, wherein said hinge means includes rollers positioned to engage said locking means in rolling contact therewith upon reception by said locking means of said hinge means.

4. An assembly according to claim 3, in which said hinge means includes a hinge pin, and said rollers are rotatably mounted on the ends of said hinge pin.

5. An assembly according to claim 1, in which said locking means comprises a plate bent to provide a hinge-receiving portion and guide surfaces diverging downwardly therefrom.

6. An assembly according to claim 3, in which said locking means comprises a plate bent to provide a downwardly opening arcuate portion to receive said rollers, and guide surfaces diverging downwardly from the ends of said

arcuate portion to guide said rollers into said arcuate portion on upward movement of said top members.

7. An assembly according to claim 4, in which cushioning means is provided for cushioning the movement of the assembly to open position, said hinge means includes a pair of brackets secured to the respective top members, and said hinge pin connects said brackets and supports said cushioning means.

8. An assembly according to claim 7, in which said brackets comprise inverted channels with said hinge pin extending through the flanges thereof, said cushioning means extending within said channels and said rollers being mounted on said hinge pin outside of said flanges.

9. An assembly according to claim 6, in which said means for raising said top members comprises an end leg structure pivotally secured to the other of said top members at a point spaced from the other end of said other top member, the length of said leg structure being greater than the spacing of said point from said other end of said other top member, said other top member folding against said leg structure on movement toward the closed position and said leg structure thereby raising said top members and moving said rollers into engagement with one of said guide surfaces and finally into said arcuate portion on completion of the movement to closing position.

10. A foldable table-type assembly comprising two top members, hinge means pivotally interconnecting one end of each of said top members for holding said members in horizontal end-to-end relation when the assembly is open and in vertical parallel relation when the assembly is closed, a wall pocket to receive said top members when the assembly is closed, means carried at the other end of one of said top members for pivotally connecting said other end in said wall pocket, locking means mounted in the upper part of said wall pocket for receiving and retaining said hinge means when the assembly is in closed position, and latching means mounted on the undersides of said top members adjacent the other ends thereof and engageable on movement of the assembly to closed position for securing said other top member to said one top member.

11. An assembly according to claim 10, in which said latching means comprises a strike carried on the underside of said one top member, and a latch carried on the underside of said other top member, said latch being spring-biased to automatically engage said strike in a locking relationship when the assembly is moved to the closed position.

12. An assembly according to claim 11, in which said latch has a handle portion extending parallel to the top member on which it is mounted and adjacent the lower end of said top member, whereby said latch may be readily released by reaching under said lower end and drawing said handle portion toward said top member.
